UNITED STATES PATENT OFFICE.

LAURENCE L. CUBBEDGE, OF GUYTON, GEORGIA.

AUTOMATIC ALARM FOR PROTECTING CROPS, &c.

SPECIFICATION forming part of Letters Patent No. 606,517, dated June 28, 1898.

Application filed September 8, 1897. Serial No. 650,983. (No model.)

To all whom it may concern:

Be it known that I, LAURENCE L. CUBBEDGE, a citizen of the United States, residing at Guyton, Effingham county, Georgia, 5 have invented a new and useful Automatic Alarm for Protecting Crops, &c., of which the following is a specification.

My invention relates to automatic alarms, and more particularly to alarms adapted to be 10 used in open fields for the purpose of protecting crops from birds, rabbits, &c., by automatic discharge of small quantities of an explosive material, such as gunpowder, at predetermined intervals.

15 The objects of my invention are to provide an apparatus of the character defined which will effectually perform its intended function without interruptions on account of wind and rain; to provide means for setting the mechanism and starting it in motion, so that the discharge may be commenced automatically at any given desired interval of time after the device is set in motion, thereby enabling the operator to set the device at any convenient 20 time of the day and permit a suitable interval of time to elapse before the explosions or discharges commence; to provide a device of the character described which will be portable, durable, and effective in action and at 25 the same time capable of economic construction, while comprising the smallest number of parts so arranged that they may be quickly and readily assembled and taken apart or adjusted, and, finally, to provide a device of 30 this character which shall be self-contained and so constructed as to minimize the shock due to the concussion following the explosions.

With these general objects in view my invention consists, essentially, in a plurality of barrels or explosive-chambers adapted to contain explosive charges provided with fuses and means arranged to operate continuously for successively igniting the said fuses, and 45 in mechanism for guarding any given number of fuses against ignition, whereby the apparatus may be set in operation at a suitable interval of time in advance of the time when it is desired that the discharges shall begin; and 50 my invention further consists in the novel construction and details of parts, as herein-after described, and more particularly pointed

out in the claims, with reference to the accompanying drawings, in which—

Figure 1 is a central vertical section of my 55 invention. Fig. 2 is a horizontal transverse section taken on the line 2 2, Fig. 1. Fig. 3 is a similar view to Fig. 2, showing the igniting device in the act of exploding its first charge, the fuse-guard being released. Fig. 4 60 is a central vertical section of the same.

Referring now to the drawings, in which the same reference-letters relate to the same parts in all the views, A indicates a suitable supporting-base, preferably of wood, circular 65 in cross-section, provided with a central recess or bore C, closed at the bottom by a sheet-metal plate a, upon which base-piece is mounted an upper foundation-block B, preferably circular in shape, centrally bored or recessed, 70 to which block is firmly secured a plurality of gun-barrels or powder-chambers E, which barrels are preferably seated in grooves formed in the upper face of the block and secured in position by staples s, the said barrels being 75 arranged at equal intervals radially around the central bore or recess in the block, with the breeches of said barrels in alinement with the said bore.

The bottom block or base-piece A and the 80 upper block B are secured together by suitable means, such as bolts b, passing upwardly through the two blocks and provided with nuts on their upper screw-threaded ends. I have shown the supporting-base of the apparatus thus made in the two pieces A and B for the reason that the device can be the more 85 conveniently handled and the different removable parts constituting the operating mechanism can be the more quickly and easily 90 assembled, adjusted, or disassembled; but I wish it understood that this base may be made in one piece of any suitable material without materially departing from the essence of my invention. 95

Mounted in the central bore of the block A is a tubular shell or casing G, provided on its outer periphery with a series of plate-brackets q, which rest in contact with the upper face of the block B, thereby firmly supporting the said casing. Slidably mounted inside of said casing G is a sleeve H, having a flanged top resting on a metal ring Q, placed inside of the casing G, opposite the breeches of the bar-

rels, said ring thus serving to partially absorb the concussion or shock due to the discharge of the barrels. Inside of the sleeve II is a second sleeve I, having a flanged top adapted to 5 rest upon the flange of the sleeve II.

Substantially in line with the vents of the barrels are perforations in the casing G, through each of which perforations extends a suitable fuse v, leading from the powder-chamber V of each barrel, the loose end of 10 said fuse passing over or through a similar perforation in the sleeve I and hanging downwardly within said sleeve between the fuse-guard plates t, secured at regular intervals on 15 the inside of said sleeve I. By this arrangement each fuse is confined between two guard-plates, so that said fuse cannot be ignited until the igniting device reaches a point between two adjacent guard-plates.

20 Mounted in the recess or bore C of the block A is a suitable clock mechanism g, confined within a casing L, which clockwork may be wound by a shaft h, passing through one side of the block A and having a crank-key i, or, if 25 desired, said clock mechanism may be wound by means of an ordinary key through a hole O in the bottom a, which hole O also serves to admit a limited amount of air upwardly through the bore C, thus assisting the draft 30 for the igniting-flame hereinafter described. Any suitable clock mechanism may be used, and inasmuch as this forms no part of my invention I do not deem it necessary to show such mechanism in detail. Attached to the 35 hour-shaft d of said clock mechanism by any suitable means, such as plate j, is a suitable lamp D, having a filling-opening e for oil and a burner f, the flame from which burner is adapted to pass successively between the several guard-plates t and ignite the fuses v as 40 the lamp is rotated by the clock mechanism.

From the foregoing description it will be seen that as the lamp rotates the flame comes in contact successively with the fuses, igniting the same, and thereby exploding the charges V, held in place by suitable wads y in each barrel. As shown in the drawings, the explosions will take place at intervals of 45 one hour, since there are twelve barrels, and 50 each revolution of the lamp will be effected in twelve hours; but it is to be understood that the number of barrels may be changed, as desired, and the predetermined intervals between successive explosions be likewise varied, as desired.

55 In order to enable the user to set the mechanism in motion at any desired time preceding that when the first explosion is desired, I provide a suitable fuse guard mechanism 60 which may be so adjusted that the lamp can be set in motion and the apparatus placed in proper position and a suitable time elapse before the first discharge takes place, after which the other discharges will follow at regular intervals. In the drawings I have shown a convenient mechanism for effecting this purpose, said mechanism consisting of a semi-

circular guard-plate l, preferably made of asbestos or tin lined with asbestos and slidably mounted in grooved ways n, formed on 70 two of the ordinary fuse-guards t, extended a suitable distance upward, which plate is supported by a spring z, connected to a rod p, which rod is fixed to a collar x, mounted on the casing G. Near one end of the lower 75 edge of the said movable fuse-guard is a perforation t', through which one of the fuses v is passed and secured, the said fuse being the one that is desired to effect the first discharge. In order to guard the other fuses, preceding 80 the one mentioned, from ignition, the guard l is drawn downward, and the fuse, passing through the perforation t', is tied in the said perforation or otherwise suitably secured therein, the loose end hanging down inside 85 the said guard-plate, while the other fuses are confined between the outer periphery of said guard and the sleeve I, thus protecting them from the flame f as the latter rotates in the direction of the arrow, Figs. 2 and 3. 90

If, for example, it is desired to set the mechanism so that the discharge will begin five hours after the device is set in motion, the clock mechanism will be wound and the lamp lighted and started, with the burner opposite 95 the first fuse covered by the guard, and in five hours the flame will have reached the other end of the guard, igniting the fuse projecting through the perforation t', as seen in Fig. 3, the burning of the said fuse releasing the guard, which, under the action of the tension-spring z, will be raised above the fuses, leaving them unprotected and in the path of the moving flame, as seen in Fig. 4, the first explosion taking place at the same 100 time and successive explosions occurring at hourly intervals.

It is to be understood that different sizes of guards may be used, according to the number of fuses it is desired to be covered by the 110 guard, depending on the length of time it is desired shall elapse between the time the apparatus is adjusted and the time at which it is desired the firing shall commence, or, as in the case shown in the drawings, the flame may 115 be started nearer the first barrel to be discharged, whereby the time elapsed will be correspondingly diminished.

In order to protect the apparatus from wind and rain, I preferably provide an upwardly-extending casing W, provided with a flange w, having projecting lips through which the bolts b pass, having nuts on their upper ends, which bolts and nuts secure said lips to the block B, the flange w resting on the tops of 125 the barrels, thereby leaving openings between the block B and the flange, through which the air may enter and pass upwardly, and mounted on the casing G is a removable chimney Y, the lower end of which is seated on the 130 collar x, and secured to the top of said chimney is a hood F, having conical perforated top and cylindrical body and above the opening of which hood is a protecting-cowl f', by

which means the lamp, barrels, the fuses, and operating mechanism are effectually protected from the rain and drafts of wind that might have a tendency to blow out the flame.

5 Attached to the base-block B is a suitable bail Z, by which the device may be readily and easily transported.

By making the chimney Y separable from the casing G, I find that the tendency of the 10 concussion to extinguish the flame is obviated, and by using the hood F, with its sides overhanging and overlapping the protecting-casing W, effective means of keeping out rain are secured, while the upward draft of air between the walls of the hood and the chimney 15 aids the central draft of the lamp to promote combustion without incurring the danger of extinguishing the flame, the latter being well protected against any strong draft tending to 20 extinguish it.

It should be noted that by causing the continuously-burning igniting device to rotate in contact with the fuses a more economical and effective apparatus is provided, since the igniting device, such as a lamp, is so much lighter in weight than the base-block and the barrels carried thereby, thus enabling the use of much simpler and cheaper mechanism for rotating the movable part, and I therefore 25 prefer to give the motion of rotation to the lamp or other igniting means rather than to the barrel-supporting structure; and, furthermore, it is found that in practical operation 30 a flame is more reliable as a means of igniting fuses connected with the explosive-chambers than friction or percussion primers, as prepared in some alarms—particularly burglar-alarms—with which I am familiar, and, moreover, such flame is simpler and less expensive than other igniting devices known 35 to me.

While I prefer the barrel-mounting to be of substantially circular shape, because I have found it to be the most effective in absorbing 40 the recoil due to concussion, my invention is not necessarily limited to this shape, and while I prefer to make the base-blocks of wood any suitable material may be used, as these and other details may be altered without departing from the main features of my 45 invention.

While my invention is specially adapted for protecting crops, it may be used for other purposes as well, such as for flushing birds, &c.

50 I claim as my invention—

1. An automatic alarm for protecting crops &c., consisting of a plurality of barrels adapted to be charged with explosive material, and arranged at intervals on a suitable base or support having a central bore or recess, fuses extending from the charges in said barrels into said bore or recess, and an igniting device arranged in said bore to ignite each fuse in succession.

55 2. An automatic alarm for protecting crops, &c., consisting of a plurality of barrels each adapted to contain an explosive charge and

arranged at intervals upon a stationary base, a moving continuously-burning igniting device adapted to ignite the charges in said barrels in succession. 70

3. An automatic alarm for protecting crops, &c., consisting of a plurality of barrels adapted to contain explosive charges arranged at intervals on a circular base having a central bore or recess, fuses extending from said charges into the said central bore, and a rotating igniting device in said bore adapted to ignite the fuses in succession. 75

4. In an automatic alarm for the purposes defined, the combination of a circular supporting-base having a central bore or recess, a plurality of barrels radially arranged at intervals around said bore or recess, fuses extending from the charges into said bore or recess, a lamp rotatably mounted in said bore or recess, and mechanism for continuously rotating said lamp so as to cause the flame thereof to ignite the fuses in succession at predetermined intervals. 80

5. In an automatic alarm for the purposes defined, the combination with a supporting-base having a central bore, of a plurality of barrels adapted to contain explosive charges radially mounted around said bore, fuses extending from the charges into said bore, a series of guard-plates between adjacent fuses, and an igniting mechanism adapted to move in contact with the fuses in succession, substantially as specified. 95

6. In an automatic alarm for the purposes defined, the combination of a supporting-base having a central bore, of a plurality of barrels adapted to contain explosive charges, fuses extending from said charges into the central bore, guards separating said fuses from one another, an igniting device with means for moving the same into contact with the fuses in succession, and means for covering one or more of said fuses to prevent ignition, substantially as described. 100

7. In an automatic alarm for the purposes defined, the combination with a supporting-base having a central bore, of a series of barrels adapted to contain explosive charges radially arranged around said bore, fuses extending from the charges into the central bore, guards between adjacent fuses, an igniting device rotatably mounted in said bore and adapted to ignite the fuses in succession, means for continuously rotating said igniting device, a movable guard adapted to cover one or more of said fuses to prevent ignition, and means for raising said guard after a predetermined interval of time, substantially as described. 115

8. In an automatic alarm for the purposes defined the combination of a series of barrels adapted to contain charges of explosive material, fuses leading from said charges, continuously-burning igniting mechanism for igniting the fuses in succession at predetermined intervals, and means for covering one or more of said fuses and preventing the com- 120 125 130

mencement of explosion until a given time has elapsed after the device is set in motion.

9. In an automatic alarm for the purposes defined, the combination with a supporting-base having a central bore, of a series of barrels adapted to contain explosive charges radially arranged around said bore, fuses extending from the charges into the bore, an igniting device rotatably mounted in said bore, and adapted to ignite the fuses in succession, a movable guard-plate covering one or more of the fuses and having a perforation therein through which a fuse may be inserted and being in the path of the igniting device, and means for moving said plate when said fuse is ignited, whereby the apparatus may be set in motion and the explosions begun at a predetermined time, substantially as described.
20. 10. The combination with the barrels adapted to contain explosive charges, the supporting-base therefor having a central bore, of a shell or sleeve in said bore provided with perforations through which the fuses extend 25 into the casing, a fuse guard-plate slidably mounted in the shell and adapted to cover one or more of the fuses, said plate being provided with a perforation through which a fuse extends and is secured, a rotating igniting device adapted to ignite said fuse and release the plate, substantially as specified.

11. In an automatic alarm for the purposes defined, the combination with a supporting-base having a central bore, of a series of barrels adapted to contain explosive charges arranged around said bore, a casing fitted in said bore provided with perforations opposite each barrel, fuses extending from the charges through said perforations, a lamp for igniting 35 said fuses in succession, a separable chimney mounted on the casing, substantially as described.

12. In an automatic alarm for the purposes defined, the combination with a supporting-base having a central bore, of a series of barrels adapted to contain explosive charges arranged around said bore, a casing fitting said bore and extending some distance above the barrels, fuses extending from the charges 40 through perforations in said casing into the bore, a lamp for automatically igniting said fuses in succession, a chimney removably mounted on the casing, and a hood having a depending body arranged to cover and protect the operating parts.

55. 13. In an automatic alarm, the combination with the supporting-base, the barrels adapted to contain explosive charges, fuses leading

from said charges, mechanism mounted in said base for igniting the fuses in succession, 60 a shell extending above the base, a casing mounted on the base and surrounding said shell, and a hood overlapping said shell and casing and covering the operating mechanism substantially as described.

65. 14. In an automatic alarm, the combination with a lower base-block having a central bore, an igniting device rotatably mounted therein, an upper block having a corresponding bore removably secured to said base-block, of a series of barrels adapted to contain explosive charges secured to said upper block, means for rotating said igniting device, and connections between said igniting device and the charges, substantially as described.

75. 15. In an automatic alarm, the combination with the supporting-base having a central bore, a tubular casing mounted in said bore and extending above the base, a series of barrels adapted to contain explosive charges radially arranged around said casing; fuses extending from the charges through perforations in said casing, a sleeve located within the casing and over or through the perforations in which the fuses pass, guard-plates 80 separating said fuses, a lamp rotatably mounted in the bore below the fuses, and mechanism for rotating said lamp, substantially as described.

85. 16. In an automatic alarm, the combination with the supporting-base having a central bore, a tubular casing mounted in said bore and extending above the base, a series of barrels adapted to contain explosive charges radially arranged around said casing; fuses extending from the charges through perforations in said casing, a sleeve located within the casing and over or through the perforations in which the fuses pass, guard-plates 90 supporting said fuses, a lamp rotatably mounted in the bore below the fuses, and mechanism for rotating said lamp, and a spring-actuated fuse guard-plate slidably mounted on the sleeve adapted to cover one or more of the fuses to prevent ignition until 95 a predetermined time has elapsed after the lamp begins to rotate, substantially as described.

100. In testimony whereof I have signed my name to this specification in the presence of 110 two subscribing witnesses.
